Carl H. Dalsgaard, R.D. 5, Driftwood Point,
Danbury, Conn.

Filed Nov. 5, 1964, Ser. No. 82,482

Term of patent 14 years

(Cl. D58—17)

FIG. 1

FIG. 2

FIG. 3

FIG. 4

FIG. 1 is a front elevational view of a dispensing tube, embodying my new design;

FIG. 2 is a side elevational view the side opposite being substantially a mirror image thereof;

FIG. 3 is a top plan view; and

FIG. 4 is a bottom plan view thereof.

From the rear, the tube appears the same as from the front except the ornamentation representing the facial features is omitted.

I claim:

The ornamental design for a dispensing tube, as shown and described.
